UNITED STATES PATENT OFFICE

LOU BRESWELL HEARLE AND HENRY GAYLE HUDSON, OF WILSON, OKLAHOMA.
ASSIGNORS OF ONE-HALF TO JONES EVERETT MACHINE CO., OF ARDMORE, OKLAHOMA

TESTING TOOL

Application filed April 30, 1931. Serial No. 534,118.

This invention relates to a device for use in testing oil, gas and water wells, one of the objects being to provide a simple and accurate tool of this character which can be produced at lower cost than devices heretofore devised for similar purposes, it being possible, by one operation, to make a complete test at any desired point in the well with much less danger than has heretofore attended the use of such devices.

10 A further object is to provide the device with novel means for packing tightly there-around so as to completely cut off the flow of fluid along the outside of the tool.

15 A further object is to provide a testing device which does not necessitate lifting the fluid above the packing and is therefore less dangerous to operate than heretofore because, simply by lifting the pipe which supports the 20 tool, a valve will be automatically closed in the tool.

25 A still further object is to provide a tool which does not necessitate the formation of a "rat hole," it being possible to get the desired results at any point in the hole made by the usual drilling operation.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the 35 scope of what is claimed, without departing from the spirit of the invention.

In the accompanying drawing, the preferred form of the invention has been shown.

40 In said drawing:

Figure 1 is a central longitudinal section through the upper portion of the testing tool in position in a well prior to the packing operation.

45 Figure 1a is a similar view through the lower portion of the device, the stop or "anchor" pipe being shown in contact with the end of the well.

50 Referring to the figures by characters of reference, 1 designates a hollow tapered mandrel the upper end portion of which is pref-

erably cylindrical as shown at 2 and provided with an interior annular shoulder 3. The upper end portion is also formed with a small interiorly screw-threaded portion 4 located above the shoulder 3. The upper end of the 55 portion 2 is exteriorly screw-threaded as at 5 so as to extend into and engage a collar 6 formed on a swedge or bushing 7 for attachment to a drill pipe.

The lower or small end of the mandrel has 60 an interior annular shoulder 8 and this shoulder extends around a central opening 9, the wall of which is screw-threaded for the reception of a pipe 10. Opposed openings 11 are formed in the mandrel 1 outside of pipe 65 10, these openings being in communication with the interior of the mandrel and with the space outside of the pipe 10.

A supporting plate 12 is provided with a central opening 13 through which the pipe 70 10 extends and this plate has a concentric depending flange 14 which is exteriorly screw-threaded for engagement by a coupling sleeve 15. By means of this sleeve a stop or "anchor" pipe 16 can be joined to the plate 75 12. This pipe can be of any desired length and is formed with apertures 17. The lower end of the pipe is preferably closed by a plug 18 to prevent sand or the like from pressing upwardly into the pipe when it is brought 80 against the bottom B of a well W.

Pipe 10 is engaged at its lower end by a coupling sleeve 19 which joins it to an apertured cap 20 supported in the stop pipe 16. Thus fluid, whether it be oil, gas or water, 85 will be free to flow through openings 17 into pipe 16 and thence through the apertured cap 20 into the pipe 10.

Mounted on the supporting plate 12 is a 90 packing sleeve 21 formed of rubber or other suitable material and provided with a central bore 22 tapered to coincide with the taper of the mandrel 1. The normal diameter of this packing sleeve is less than the internal 95 diameter of the well to be tested.

The lower end portion of the mandrel 1 is normally seated in bore 22 and it is to be understood that when the mandrel is forced downwardly relative to the packing sleeve, 100 said sleeve will be expanded radially into

tight engagement with the wall of the well, thereby producing a tight seal.

The shoulder 3 in the mandrel constitutes a seat for a ring 23 supporting a disk 24.

- 5 It is preferred to interpose a gasket 25 between the ring and disk for use as a seal. Disk 24 is held tightly in position by a threaded ring 26 which engages the threaded portion 4 of the mandrel.
- 10 Disk 24 has a central opening 27 and at the lower end of this opening is a tapered valve seat 28. The upper end of the opening 27 is flared as at 29 so as to communicate with apertures 30 formed in a guide plate 31 which is seated in a recess 32 provided therefor in disk 24. The apertures 30 open into a compartment A in the upper portion of the mandrel.

15 In the guide plate is mounted a sleeve 33 the lower enlarged end 34 of which is seated within but spaced from the wall of opening 27. Slidable in this sleeve is a valve stem 35 provided with a tapered annular shoulder 36 which normally engages a tapered seat 37 formed about an opening 38 in a valve 39. This valve is adapted normally to engage the seat 28, it being held thereto by a spring 40 which is mounted on sleeve 33. One end of this spring bears upon the abutment plate 31 while the other end thrusts against a washer 42 which, in turn, is restrained by nuts 43 engaging the upper end of stem 35.

20 Because of the constant tension of spring 40 the tapered shoulder 36, which constitutes a supplemental valve, is normally pressed against its seat 37 while valve 39 is normally pressed against its seat 28.

25 The supplemental valve 36 has an extension 44 and pivoted in this extension at 45 is an equalizer 46 to the end portions of which are pivotally connected oppositely extending levers 47. These levers are fulcrumed in brackets 48 depending from disk 24 and the outer ends of the levers have elongated fingers 49 pivotally connected to them. The lower ends of these fingers are slightly offset out of alinement as shown at 50 so as to extend normally along substantially parallel lines and project through and downwardly 50 below the openings 11 into the space between pipe 10 and the wall of bore 22.

55 When making a test a sufficient amount of pipe 16 is connected to plate 12 to stop the plate 12 at the point where the test is to be made, the tool being limited in its downward movement by contact of the lower end of pipe 16 with the bottom of the well. As the tool is supported by a pipe connected to the swedge 7, there will be no expansion of the packing sleeve 21 while the tool is being lowered. However when the tool is brought to the lower limit of its movement, the weight of the pipe thereabove will force the mandrel 1 downwardly relative to the packing sleeve 21. 60 65 This will cause said sleeve to expand radially

into tight engagement with the wall of the well, thereby preventing flow of fluid upwardly or downwardly along the outer side of the tool.

70 As the mandrel 1 moves downwardly the lower ends 50 of the fingers 49 come into contact with plate 12. This results in actuation of levers 47 the inner ends of which will swing downwardly. During this action the valve 36 will first be disengaged from its seat 37 and fluid will escape upwardly through the opening 38 to relieve upward pressure on the valve 39. This last valve will subsequently be opened by pressure of the end 34 of sleeve 33 thereagainst. The time 80 interval during which fluid under pressure can escape upwardly around valve 36 will depend on the distance between valve 39 and flange 34. This distance is regulated by adjustment of the nut 43 on stem 35. The valve 85 of valve 36 as a means for relieving valve 39 from excessive upward pressure will, of course, depend upon the relative areas of the two valves. The fluid will rise within the tool through opening 27 and from the height 90 that the fluid rises in the tool and in the pipe thereabove in a given time, the operator can determine the production of the well at the point of test. When it is desired to remove the tool it is lifted by means of the pipe connected thereto and as soon as it starts upwardly the fingers withdraw from contact with plate 12 and the valves snap shut.

95 A bumper ring 51 is mounted on the mandrel at the lower part of its cylindrical portion 2 and acts to limit the movement of the mandrel downwardly into the packing sleeve 21. It also acts to protect the packing sleeve while it is being pulled with the tool out of the hole.

100 By means of the nuts 43 the compression of the spring 40 can be varied so that the desired amount of fluid can be retained by the valves.

105 What is claimed is:

110 1. A tool of the class described including a tapered mandrel having a compartment therein provided with an inlet opening, a pipe extending from the mandrel having an inlet, an expandible packing sleeve supported about the mandrel, a slidble connection between said sleeve and the pipe, means connected to the sleeve for limiting the downward movement of the sleeve within a well, said sleeve being expandible into sealing contact with the wall of a well by the mandrel when lowered relative thereto, and means within the mandrel and extended outside of the pipe for operation by the downward movement of the mandrel relative to the packing sleeve for establishing communication between the lower end of the mandrel and the compartment.

115 2. A device of the class described including a supporting element, means depending therefrom for limiting the downward move-

120

125

130

ment of said element in a well, an expandible packing sleeve mounted on said element, a tapered hollow mandrel opening downwardly through said element and shiftable relative thereto to expand the packing sleeve into sealing contact with the wall of a well, a compartment in the mandrel having an inlet, a valve normally closing the inlet, and means in the mandrel and located entirely above the element supporting the packing sleeve, for actuation by the movement of the mandrel in one direction relative to said element for opening the valve.

3. A device of the class described including a supporting element, means depending therefrom for limiting the downward movement of said element in a well, an expandible packing sleeve mounted on said element, a tapered hollow mandrel opening downwardly through said element and shiftable relative thereto to expand the packing sleeve into sealing contact with the wall of a well, a compartment in the mandrel having an inlet, a valve normally closing the inlet, means within the mandrel and above the supporting element for actuation by the movement of the mandrel in one direction relative to said element for opening the valve, and means for automatically closing the valve when the mandrel is moved in the opposite direction relative to the sleeve.

4. A tool of the class described including an expandible packing sleeve, means connected thereto for limiting the downward movement of the sleeve in a well, a tapered hollow mandrel projecting into the sleeve, separate means movable with the mandrel for limiting the relative upward and downward movement respectively of the mandrel and sleeve, a compartment having an inlet, a main valve for closing the inlet, said valve having an opening and a seat, a supplemental valve normally closed against the seat on the main valve, yielding means for holding the valves normally upon their respective seats, and means operated by the mandrel when approaching the limit of its downward movement for opening the supplemental and the main valves successively, said means including a lever connected to the supplemental valve and a finger depending from the lever and projecting from the lower end of the mandrel.

In testimony that we claim the foregoing as our own, we have hereto affixed our signatures.

LOU BRESWELL HEARLE.
HENRY GAYLE HUDSON.
